UNITED STATES PATENT OFFICE

128,802

DESIGN FOR A CHAIR

Robert R. Scheinfield, Philadelphia, Pa.

Application November 22, 1940, Serial No. 96,741

Term of patent 14 years

To all whom it may concern:

Be it known that I, Robert R. Scheinfield, a citizen of the United States, residing at Philadelphia, in the county of Philadelphia and Commonwealth of Pennsylvania, have invented a new, original, and ornamental Design for a Chair, of which the following is a specification, reference being had to the accompanying drawings forming a part thereof, in which

I claim:

The ornamental design for a chair, as shown.

ROBERT R. SCHEINFIELD.
